UNITED STATES PATENT OFFICE.

PAUL S. LUTTRELL AND PAUL C. ROSKE, OF OAKLAND, CALIFORNIA.

TIMING DEVICE.

Application filed March 21, 1921. Serial No. 453,924.

To all whom it may concern:

Be it known that we, PAUL S. LUTTRELL and PAUL C. ROSKE, citizens of the United States, and residents of Oakland, county of Alameda, and State of California, have invented a certain new and useful Timing Device, of which the following is a specification.

The invention relates to timing devices and particularly to what may be known as interval clocks or clocks that are adapted to be set to run for a predetermined period of time, and at the end of that period stop running and at the same time sound an alarm, giving notice that the predetermined interval of time has elapsed.

An object of the invention is to improve the construction of the device of the character described to make it fool-proof, simple and substantial and cheap to manufacture.

Another object of the invention is to provide an improved alarm trip mechanism.

A further object of the invention is to provide means for preventing turning of the winding key in the wrong direction.

The invention possesses other advantageous features, some of which, with the foregoing, will be set forth at length in the following description, where we shall outline in full, that form of the invention which we have selected for illustration in the drawings accompanying and forming part of the present specification. In said drawings, we have shown one embodiment of our invention, but it is to be understood that we do not limit ourselves to such form, since the invention, as expressed in the claims, may be embodied in a plurality of forms.

Referring to said drawings:

Figure 1 is a front elevation of the device of our invention.

Fig. 2 is a side elevation of the mechanism, removed from the casing.

Fig. 3 is an enlarged section of the winding mechanism.

Fig. 4 is a front view of the alarm trip controlling disc.

Fig. 5 is a similar view on a larger scale, showing the position of the parts when the alarm mechanism is released.

Fig. 6 is a rear view of the alarm trip controlling disc.

Fig. 7 is a detail of the gear for releasing the alarm trip controlling device.

Fig. 8 is a detail of the coacting gear for preventing reverse rotation of the winding key.

Fig. 9 is a detail of the mechanism for locking together the alarm shaft and the time shaft.

Fig. 10 is a rear elevation on an enlarged scale, of the timing device, with the winding key removed.

The device comprises a suitable casing 2 in which the clock mechanism is disposed, the mechanism being arranged between suitable bearing plates 3, 4 and 5. The casing is provided with a graduated dial 6, over which the indicator hand 7 moves. The clock mechanism is divided into two groups, one group of gears operating an alarm device and the other gear train operating the indicator hand and a trip mechanism for the alarm. The alarm bell 8 is preferably disposed within the casing.

The alarm spring 9 and the time spring 12 are wound by the key 13, means being provided whereby the initial rotation of the key 13, in this instance the first two revolutions of the key, winds the alarm, and the further rotation of the key winds both the alarm spring 9 and the time spring 12 and moves the indicator hand 7 over the dial 6 to the desired setting. The alarm spring shaft 15 is hollow and the time spring shaft 16 extends through the alarm spring shaft and the three bearing plates 3, 4, 5, and carries the indicator hand on its forward end. At its rear end, the alarm spring shaft 15 is provided with a squared extension 17 on which seats the gear or disc 18, having a single tooth 19. This gear is provided on its rear surface with single depression ratchet 21, which is engaged by the spring-pressed pawl 22, pivoted to the gear or disc 23, which is also provided with a single tooth 24. The gear 23 is loosely mounted on the time shaft 16 and is disposed directly behind the gear 18, so that the pawl engages the ratchet 21 when the gear 23 is turned in the winding direction. The gear 23 is provided on its rear face with a hollow extension or neck 25 which passes through the bearing bridge 26 and which is provided with bayonet slots 27 for engagement with pins 28 on the shank of the key. Rotation of the key 13 in the winding direction, therefore causes

the gear 23 to turn, and the pawl 22 is caused to engage the ratchet 21, so that the gear 23 is turned in the winding direction. The gear 23 is provided on its rear face with a hollow extension or neck 25 which passes through the bearing bridge 26 and which is provided with bayonet slots 27 for engagement with pins 28 on the shank of the key. Rotation of the key 13 in the winding direction, therefore causes

- 2
- rotation of the gear 18 which is secured to the alarm spring shaft. Rotation of the key in the wrong direction and the probable injury of the clock or alarm mechanism is prevented by the Geneva stop gear 29, journaled on the shaft 31 secured to the rear bearing plate 3 and adapted to be engaged by the tooth 24 of gear 23. By virtue of this arrangement, the key may be turned backward freely, after the alarm has been wound a distance equal to the amount of winding, but no further, and before winding, the key cannot be turned backward. When the alarm is tripped, the alarm spring shaft rotates backward and such movement is also halted by the Geneva stop gear. In the present construction this gear is designed to permit three full turns of the key in winding and setting, but no more.
- 20 Means are provided for causing engagement of the key with the time spring shaft 16 to wind the time spring and set the indicator, after the key has been rotated a definite distance in winding the alarm, in the present instance, after the alarm shaft has been given two full turns. Secured to the time spring winding shaft 16, in the present instance by engagement with the screw threaded portion 32 thereof, and bearing against the end of shaft 15, so that it rotates with shaft 16, is a gear 33 having a single tooth 34, which engages with a Geneva stop gear 35, rotatably mounted on the rear face of gear 23. The Geneva stop gear 35 is so disposed, that after two complete revolutions of the gear 23, the Geneva stop 35 jams in engagement with the tooth 34 and causes the shafts 15 and 16 to rotate in unison.
- 40 Secured to the front end 36 of the shaft 16, is the indicating hand 7, which moves over the dial as the shaft is rotated. Secured to the shaft 16, behind the dial, is a disc 37 having a notch 38 therein, which controls the alarm trip lever 39, which is attached to the vibratory shaft of the alarm hammer 41. When the trip is released, the shaft is vibrated by the alarm mechanism and the alarm is sounded. When the indicator points to zero on the dial, the end of the trip lever 39 overlies the notch 38, and when the indicator is moved over the dial, the disc is moved through a corresponding angle, so that as the indicator is moved backward toward zero by the clock mechanism, the disc is synchronously moved backward, bringing the notch under the end of the trip lever when the indicator reaches zero, thus freeing the end of the trip lever and permitting it to vibrate.
- 60 Means are provided for stopping the alarm after it has sounded for a predetermined time and for preventing the alarm from sounding while the alarm spring is being wound and before the indicator is

moved. Lying in front of and in contact with the disc 37, is a sector shaped plate 42, mounted on the time shaft 16 and having a periphery partly concentric with and of the same diameter as the disc and partly eccentric with and of less diameter than the disc. When the eccentric portion 43 is contiguous to the notch 38, the notch is open and when the concentric portion 44 is contiguous to the notch, the notch is closed. In Fig. 4, the notch is shown closed, and in Fig. 5 is shown open. The plate 42 is continually pressed in a direction tending to close the notch, by a spring 45, secured to the disc 37 and engaging a bearing plate 46 on the plate 42.

Means are provided for opening the notch and holding it open for the interval during which it is desirable to have the alarm sound. Journaled in the bearing plates 3, 4 and 5 is a shaft 47, having an arm 48 secured thereto at the forward end, the arm lying in front of the plate 42. The arm 48 is pressed inwardly by a spring 49, surrounding the shaft 47. At its end the arm 48 is provided with a tooth 51 adapted to engage a pin 52 on the plate 42 and hold the plate against the action of the spring 45, thereby holding the notch open. At its rear end, the shaft 47 is provided with an arm 53, secured thereto, which lies between the Geneva stop gears 29 and 54 journaled on the shaft 31. The lower Geneva stop gear 54 is provided on its upper surface with a pin 55, which, as the Geneva gear 54 rotates, moves into engagement with the arm 53, moving it outward and consequently moving the arm 48 outward, releasing the pin 52 and permitting the plate 42 to move to close the notch. The pin 55 is so placed that it engages the arm 53 and moves it outward, just as the key reaches its initial unwound position. The Geneva stop gear 54 is rotated by engagement with the tooth 19 on the gear 18, which is fixed to the alarm shaft 15.

The clock mechanism is stopped when the indicator moves back to zero, by engagement of the pin 56, on the rear face of the disc 37, with a stop 57 on the bearing plate 5. The pin 56 is preferably disposed in a short circumferential slot 58 in the disc 37, to permit rotation of the disc through 360° to give the device a setting range over the whole dial.

In operation, the key is turned to wind the alarm, and time springs, and move the indicator through the desired angle on the dial. The indicator is then moved backward over the dial by the action of the main clock spring 12 controlled by the escapement movement 59, which is connected by suitable gearing with the main driving gear 61 which is in tight frictional engagement with the indicator shaft 16. With the arrival of the indicator hand at zero, the alarm trip is

released, the alarm sounded, causing a reverse movement of the shaft 15, which operates the mechanism to close the notch and stop the alarm.

5 The dial may be graduated in any desired time units and the timing mechanism is constructed to move the indicator over the dial at the proper speed. The dial may be graduated in seconds or minutes, or any other desirable time interval, and the timing mechanism is so arranged that it moves the indicator over the dial at a speed corresponding to the graduations of the dial.

We claim:

1. In a timing device, an alarm mechanism and its spring actuated driving mechanism, an indicator, at the front of the device and a spring actuated driving mechanism therefor, a pair of concentric shafts, one of which is connected to the alarm mechanism and the other of which is connected to the indicator driving mechanism, a key at the rear of the device for turning the alarm mechanism shaft, and means connected to the key and operative after a complete revolution of the alarm mechanism shaft, for securing said shafts together.

2. In a timing device, an alarm mechanism and its spring actuated driving mechanism, an indicator and a spring actuated driving mechanism therefor, a shaft connected to the alarm mechanism, a shaft connected to the indicator driving mechanism, a gear secured to the first shaft, a second gear rotatable on said shaft, a pawl on said second gear adapted to engage a ratchet tooth on the first gear for movement of the second gear in one direction, said ratchet tooth, a key attached to said second gear, and means for limiting the motion of said key in the opposite direction.

3. In a timing device, an alarm mechanism and its spring actuated driving mechanism, an indicator and a spring actuated driving mechanism therefor, a shaft connected to the alarm mechanism, a shaft connected to the indicator driving mechanism, a key connected to said first shaft, means operative by more than one revolution of the key in the winding direction for securing said shafts together, and means for limiting the reverse movement of the key.

4. In a timing device, an alarm mechanism and its spring actuated driving mechanism, an indicator and a spring actuated driving mechanism therefor, a shaft connected to the alarm mechanism, a shaft connected to the indicator driving mechanism, a sleeve turnably mounted on the last named shaft, a winding key on said sleeve, means forming an automatic coupling between said sleeve and the first named shaft to turn said shaft and the sleeve in unison, and other means carried by the sleeve adapted to form an automatic coupling between the sleeve

and the second named shaft when the sleeve and the first named shaft have been turned in unison a predetermined distance.

5. In a timing device, an alarm mechanism and its spring actuated driving mechanism, an indicator and a spring actuated driving mechanism therefor, a shaft connected to the alarm mechanism, a shaft connected to the indicator driving mechanism, a gear secured to said alarm shaft, a second gear disposed axially with respect to said first gear and adapted to engage said first gear upon rotation of the second gear in one direction, a tooth on said second gear and a reverse rotation stop gear arranged to be engaged by said tooth to stop rotation in the opposite direction.

6. In a timing device, an alarm mechanism and its spring actuated driving mechanism, an indicator and a spring actuated driving mechanism therefor, a pair of shafts one disposed within the other, one of said shafts being connected to the alarm mechanism and the other being connected to the indicator driving mechanism, winding means engaging said first shaft and surrounding said second shaft, a toothed element secured to said second shaft and a Geneva stop gear carried by the winding means and arranged to engage said tooth.

7. In a timing device, an alarm mechanism and its spring actuated driving mechanism, an indicator and a spring actuated driving mechanism therefor, a pair of shafts one disposed within the other, one of said shafts being connected to the alarm mechanism and the other being connected to the indicator driving mechanism, a disc arranged to engage said first shaft, a cylindrical extension on said disc surrounding said second shaft, a winding key attached to said extension, a toothed element secured to said second shaft and disposed within said projection, and a Geneva stop gear rotatably mounted on said disc and disposed to engage said toothed element.

8. In a timing device, an alarm mechanism and its spring actuated driving mechanism, an indicator and a spring actuated driving mechanism therefor, a shaft to which said indicator is secured, a notched disc secured to said shaft and an alarm trip mechanism engaging the periphery of said disc and adapted to be released by movement of the disc to bring the notch into cooperative relation with the trip mechanism, said trip mechanism including a sector plate operatively mounted on the indicator shaft.

9. In a timing device, an alarm mechanism and its spring actuated driving mechanism, an indicator and a spring actuated driving mechanism therefor, a shaft to which said indicator is secured, a notched disc movable with said shaft, an alarm trip mechanism engaging the periphery of the

disc and adapted to be released by movement of the notch into registry with the end of the trip mechanism, and a sector plate operative by the subsequent rotation of the alarm shaft, for closing said notch.

10. In a timing device, an alarm mechanism and its spring actuated driving mechanism, an indicator and a spring actuated driving mechanism therefor, a shaft to which said indicator is secured, a notched disc movable with said shaft, an alarm trip mechanism engaging the periphery of the disc and adapted to be released by movement of the notch into registry with the end of the trip mechanism, a plate arranged contiguously with said disc and having a portion adapted to overlie and close said notch, an arm controlling the movement of said plate, and means operative by the movement of the alarm shaft for moving said arm.

11. In a timing device, an alarm mechanism and its spring actuated driving mechanism, an indicator and a spring actuated driving mechanism therefor, a shaft to which said indicator is secured, a notched disc movable with said shaft, an alarm trip mechanism engaging the periphery of the disc and adapted to be released by movement of the notch into registry with the end of the trip mechanism, a plate arranged contiguously with said disc and having a portion adapted to overlie and close said notch, said plate being in frictional contact with said disc, a pin on said plate, an arm adapted to engage said pin and hold the plate against movement during motion of the disc to open said notch, and means operative by the movement of the alarm shaft for moving said arm to release said plate.

12. In a timing device, an alarm mechanism and its spring actuated driving mechanism, an indicator and a spring actuated driving mechanism therefor, a shaft to which said indicator is secured, a notched disc movable with said shaft, an alarm trip mechanism engaging the periphery of the disc and adapted to be released by movement of the notch into registry with the end of the trip mechanism, a plate arranged contiguously with said disc and having a portion adapted to overlie and close said notch, said plate being in frictional contact with said disc, a pin on said plate, an arm adapted to engage said pin and hold the plate against movement during motion of the disc to open said notch, means operative by the movement of the alarm shaft for moving said arm to release said plate, and a spring secured to the disc and bearing against the plate to move the plate to close the notch.

13. In a timing device, an alarm mechanism and its spring actuated driving mechanism, an indicator and a spring actuated driving mechanism therefor, a shaft to which said indicator is secured, a notched

disc movable with said shaft, an alarm trip mechanism engaging the periphery of the disc and adapted to be released by movement of the notch into registry with the end of the trip mechanism, a plate arranged contiguously with said disc and having a portion adapted to overlie and close said notch, said plate being in frictional contact with said disc, a pin on said plate, an arm adapted to engage said pin and hold the plate against movement during motion of the disc to open said notch, a shaft to which said arm is secured, an arm on the other end of the shaft, a gear on the alarm shaft, a gear in mesh therewith, and means on the second gear for engaging said second arm to release said plate.

14. In a timing device, an alarm mechanism and its spring actuated driving mechanism, an indicator and a spring actuated driving mechanism therefor, a shaft to which said indicator is secured, a disc secured to said shaft, a stop pin mounted on said disc and a fixed stop adapted to be engaged by the pin to stop the indicator driving mechanism.

15. In a timing device an alarm mechanism and a spring actuated driving mechanism, an indicator, a spring actuated driving mechanism therefor, means for winding the alarm mechanism, means forming a coupling to wind the indicator actuating spring and to turn the indicator hand in one direction when the alarm spring has been wound a predetermined amount, and means for manually turning the indicator hand independently of the alarm winding mechanism and the coupling means in the opposite direction, said manual means also adapted to unwind the indicator driving spring a proportional amount.

16. In a timing device of the character described a shaft, a main spring adapted to be wound thereby, an indicator hand secured to said shaft, a sleeve turnably mounted on the shaft, a second sleeve turnably mounted on the shaft, an alarm spring adapted to be wound thereby, an alarm mechanism actuated by the alarm spring, a winding key on the first named sleeve, means on said sleeve engageable with the second named sleeve to permit turning of the sleeves in unison, and other means forming an automatic coupling between the first named sleeve and the shaft when both sleeves have been turned in unison a predetermined distance.

17. In a timing device of the character described a shaft, a main spring adapted to be wound thereby, an indicator hand secured to said shaft, a sleeve turnably mounted on the shaft, a second sleeve turnably mounted on the shaft, an alarm spring adapted to be wound thereby, an alarm mechanism actuated by the alarm spring,

a winding key on the first named sleeve, means on said sleeve engageable with the second named sleeve to permit turning of the sleeves in unison, and a Geneva stop movement carried by the first named sleeve and adapted to form a lock between the first named sleeve and the shaft to turn the same when both sleeves have been turned in unison a predetermined distance.

18. In a timing device of the character described a shaft, a main spring adapted to be wound thereby, an indicator hand secured to said shaft, a sleeve turnably mounted on the shaft, a second sleeve turnably mounted on the shaft, an alarm spring adapted to be wound thereby, an alarm mechanism actuated by the alarm spring, a winding key on the first named sleeve, means on said sleeve engageable with the second named sleeve to permit turning of the sleeves in unison, other means forming an automatic coupling between the first named sleeve and the shaft when both sleeves have been turned in unison a pre-

determined distance, and an alarm release mechanism actuated by the second named sleeve.

19. In a timing device of the character described, an alarm mechanism, a spring actuated driving mechanism operating the same, an indicator hand, a spring actuated driving mechanism therefor, a key for winding the alarm mechanism spring, automatically actuated means forming a coupling to wind the indicator spring when the alarm spring has been turned a predetermined distance and to turn the indicator hand, and means for manually turning the indicator hand independently of the alarm winding key and the automatic coupling, said manual means also adapted to unwind the indicator driving spring.

In testimony whereof we have hereunto set our hands at San Francisco, California, this 9th day of March, 1921, and the 8th day of October, 1919, respectively.

PAUL S. LUTTRELL.
PAUL C. ROSKE.
